The ornamental design for a reflector for lighting fixture, as shown and described.

DESCRIPTION

FIG. 1 is a perspective view of a reflector for lighting fixture showing our new design;

FIG. 2 is a front elevational view thereof;

FIG. 3 is a right side elevational view thereof; the left side elevational view is a mirror image of the right side elevational view;

FIG. 4 is a top plan view thereof;

FIG. 5 is a bottom plan view thereof;

FIG. 6 is an enlarged view thereof taken in the direction of arrows 6—6 in FIG. 2;

FIG. 7 is a cross-sectional view thereof taken in the direction of arrows 7—7 in FIG. 6; and,

FIG. 8 is a cross-sectional view thereof taken in the direction of arrows 8—8 in FIG. 6.

The broken lines shown in FIGS. 1 to 8 are for illustrative purposes only and form no part of the claimed design.
